DESIGN FOR A LADY'S SMOKING PIPE

Harriet Sacks, New York, N. Y.

Application March 15, 1945, Serial No. 118,502

Term of patent 14 years

(Cl. D85—8)

To all whom it may concern:

Be it known that I, Harriet Sacks, a citizen of the United States of America, residing in the city of New York, county of the Bronx, and State of New York, have invented a new, original, and ornamental Design for a Lady's Smoking Pipe, of which the following is a specification, reference being had to the accompanying drawing, forming part thereof.

In the drawing:

Fig. 2 is an elevational view thereof.

I claim:

The ornamental design for a lady's smoking pipe, substantially as shown.

HARRIET SACKS.
